(57) **CLAIM**

The ornamental design for a transparent computer stand, as shown and described.

DESCRIPTION

FIG. 1 is a front perspective view of the new design; FIG. 2 is a rear view thereof; FIG. 3 is a front view thereof; FIG. 4 is a right side view thereof (the left side view is a mirror image); and, FIG. 5 is a top view thereof (the bottom view is a mirror image).

The broken lines shown in the drawings represent portions of the transparent computer stand that form no part of the claimed design.
